PRESSURE SWITCH WITH LOW
PRESSURE CUT-OUT

Irving W. Krieger, Sr., St. Charles, and Edwin A. Par-
mann, Batavia, Ill., assignors, by mesne assignments, to
Furnas Electric Company, Batavia, Ill., a corporation
of Delaware

Filed Aug. 28, 1962, Ser. No. 219,938
7 Claims. (Cl. 200—67)

The invention relates to electric switches, and has reference more particularly to pressure actuated switches having mechanism for effecting an opening of the contacts of the switch at a low pressure below the low pressure of the normal operating range.

The pressure switch of the invention employs the basic switch elements as shown in the Elsner and McGary Patent No. 3,015,006, granted December 26, 1961, the said elements including a toggle member having snap action in response to certain pressure conditions to effect opening and closing of the contacts of the switch. Heretofore low pressure cut-off required two separate switches, one to operate between the normal low and high pressure range, and a second switch connected in series with a manual reset for opening the contacts in the event the pressure should fall below that of the normal operating range. This sometimes happens when the pressure fluid fails completely for some reason or other.

The switch of the invention incorporates mechanism in addition to that shown in Patent No. 3,015,006 which, without interfering with the normal operation of the switch, also provides a cut-out at a third pressure that is below the low pressure of the normal operating range. A reset lever is provided for obtaining normal operation of the switch and which must be held depressed by the operator until the pressure in the system builds up to exceed that of the low pressure switch-closing setting. The switch thereafter will automatically maintain the pressure requirements of the system.

Another object of the invention is to provide a switch having a low pressure cut-off as described and which will have general utility as regards pressure switch application and uses, since all of the contacts of the switch may be the normally closed or the normally open type with both of the connecting members being either push rods or pull rods, respectively.

With these and various other objects in view the invention may consist of certain novel features of construction and operation, as will be more fully described and particularly pointed out in the specification, drawings and claims appended thereto.

In the drawings which illustrate an embodiment of the device and wherein like reference characters are used to designate like parts—

FIGURE 1 is an elevational view showing a pressure switch having incorporated therein the improved features of the invention;

FIGURE 2 is a vertical sectional view through the switch device of FIGURE 1 taken substantially on line 2—2 of said figure;

FIGURE 3 is a sectional view on line 3—3 of FIGURE 1 and showing the pressure lever and adjustable coil spring which form part of the toggle mechanism of the switch;

FIGURE 4 is a horizontal sectional view showing the toggle member and tensioning spring and which is taken substantially along line 4—4 of FIGURE 2;

FIGURE 5 is a sectional view taken horizontally on line 5—5 of FIGURE 2;

FIGURE 6 is a top plan view of the contact block of the switch and which is taken substantially on line 6—6 of FIGURE 2;

FIGURE 7 is a vertical sectional view through the

2

switch of FIGURE 1 and which shows the position of the parts when the pressure fluid has failed completely; and

FIGURE 8 is a vertical sectional view similar to FIGURE 7, but showing the position of the parts during normal operation.

The pressure switch of FIGURE 1 has been selected for illustrating the improved features of the invention and which are best shown in FIGURES 7 and 8. The basic structure of the switch proper includes an adaptor or base portion 10 having a threaded inlet 11 for admitting a fluid under pressure, said base portion 10 being secured by the screws 12 to the supporting ring 13 of the switch structure. The bottom wall 14 of the housing 15, together with the flexible diaphragm 16 are interposed between the parts 10 and 13 so that the switch structure, housing and adaptor are fixedly joined together as a unit. The bottom wall 14 of the housing has an opening 17 in alignment with the inlet so that the pressure fluid in the inlet is in direct contact with the undersurface of the diaphragm 16 to flex the same in a manner depending on the pressure conditions to which the diaphragm is subjected. The toggle mechanism of the present switch is in turn actuated by the flexing of the diaphragm 16 and as the toggle mechanism is caused to oscillate from one side 25 of a dead center position to the other, the contacts of the switch are respectively actuated.

The supporting ring structure 13 is accordingly fixedly secured to the housing 15 and said ring structure has associated therewith the frame assembly 20 and the pivot device comprising the pivots 21 for the pressure lever 22, the said lever comprising the actuating means for the toggle member as will be presently described. The frame assembly 20 as best shown in FIGURES 2 and 3 provides the upstanding side walls 23 and 24 which are bent outwardly at their upper ends to form the flanges 25 and 26. Said flanges in turn support the contact block which is designated in its entirety by the numeral 28. The screws 27 extend through side extensions formed on the contact block and the said screws are threaded into the flanges 25 and 26 for releasably securing the contact block to the frame assembly 20. The side walls 23 and 24 are each slotted or notched at 30, FIGURES 7 and 8, and the pivot ends of the lever 22 are located in the notches for pivotally mounting the lever on the frame assembly 20 with the movable end of the lever 22 being disposed at the right as in FIGURES 1, 7 and 8.

The coil spring 32 has encircling relation with the rod 33 which is anchored at its base end in the ring structure 13, and which extends upwardly from the structure to approximately the top surface of the contact block 28. The top end of the coil spring 32 is confined by the cap 34 which is threaded on the upper end of the rod 33. The cap can be adjusted on said rod as regards its vertical position so as to vary the compressive force exerted by the coil spring on the lever 22.

The pivot device providing the pivots 21 includes the base 35 and which is located in contact with the flexible diaphragm 16 on the top side thereof and thus the pivot device will move bodily in a vertical direction as the pressure fluid on the diaphragm causes the same to flex. This bodily movement of the pivots 21 will be transmitted to the lever 22 and accordingly the said lever will oscillate on its pivot axis 30.

One of the improvements of the invention resides in the provision of a flat spring member 36, one end of which is retained between the head of the rod 33 and the wall of the ring 13. The other end of the spring member 36, and which is the left end as seen in FIGURES 7 and 8, is riveted at 37 to the base 35 and also to the diaphragm 16, the rivet 37 extending through the several parts. The tension exerted by the flat spring member 36 is downward so that the base 35 and the

pivots 21 are yieldingly biased in a downward direction.

The toggle member 38 having the shape as shown in FIGURE 4 is pivotally mounted at its extremities as at 40 on the upstanding side walls 23 and 24 of the frame assembly 20. Whereas the pivot ends 30 for the lever 22 are located at the left edge of each side wall, the pivot extremities 40 of the toggle member 38 engage in notches on the right edge of the said side walls. Also whereas the lever 22 is disposed in surrounding relation with the frame assembly 20, the toggle member 38 is located within the frame assembly. This locates the movable end of the toggle member adjacent the headed screw 41 located in plate 42. Said screw is adjustable in a vertical direction to limit upward movement of the toggle member 38 which has its downward movement limited by the bottom wall of the frame assembly 20. The toggle structure of the switch is completed by the coil spring 43 which is retained at its left hand end by the toggle member and at its right hand end by the nose formed on the pressure lever 22.

The contact block assembly 28 which is fixedly secured to the frame assembly 20 by the screws 27 is preferably formed of a moldable plastic although other insulating materials may be used. Said block is cored externally to provide the recesses for receiving the metal strips 45 on one side of the contact block FIGURE 6 and the metal strips 46 on the other side. The terminal screws 47 secure the metal strips 45 to the block whereas the screws 48 secure the strips 46 to the block and said screws extend into internal recesses and provide the stationary contacts of the switch. The screws 48 provide the contacts for the movable contact bar 50 and the screws 47 provide the contacts for the movable contact bar 51 which is not shown, but which is similar to bar 50. Each bar is carried by a pull rod 52 in combination with a coil spring 53, as shown in FIGURES 7 and 8. A pair of the spaced pull rods 52 is shown in FIGURE 3. The coil springs are each confined between its contact bar and the insulating closure plate 54 through which the pull rods extend. The coil springs 53 exert a compressive force against its contact bar to cause the respective bar to close against the contacts of the terminal screws 47 and 48, respectively. Each pull rod 52 has a head portion 55 which is located above the contact bar so that when the pull rod is pulled down it also moves its contact bar in a downward direction to open the contacts.

The pull rods are each formed with a hook portion 56 and which extend through openings in the toggle member 38 and engage under the side extensions 57 of the actuating lever 58, FIGURES 5, 7 and 8. The actuating lever is part of the present improvement in that said lever effects the opening of the switch contacts when the pressure on the diaphragm 16 fails completely.

The actuating lever 58 is pivoted on respective sides by the U-shaped wire member 60, the ends of which pass through the arms of the lever and also through the upstanding supports 61. Since the actuating lever is located below the toggle member and also below the pressure lever, these two elements have certain particular action on the actuating lever. The hook ends of the pull rods extend through openings in the toggle member and said hook ends are located under the lateral extensions 57 of the actuating lever. When the toggle member moves down the actuating lever is also caused to move down and this pulls on the rods 52 to effect an opening of the switch contacts. However, when the toggle member moves up the actuating lever is not influenced by it, but by the coil springs 53 which move the contact bars 50 and 51 into closing relation with the stationary contacts provided by the terminal screws 47 and 48. This spring action of the coil springs 53 will move the pull rods in an up direction and so the actuating lever is caused to follow the toggle member when it moves upwardly.

This up and down snap movement of the toggle mem-

ber is caused by the pressure lever in moving to and from positions above and below dead center. Such action, will take place during normal pressure conditions and, accordingly, the contacts open when a pre-set high pressure is reached and the contacts close when a pre-set low pressure is reached. Should the pressure fluid fail completely then the pivot device, including the base 35 and the pivots 21, is caused to drop since the flexible diaphragm 16 is not under any pressure and, in addition, the flat spring member 36 yieldingly biases the pivot device in a down direction. This action drops the pressure lever 22 and said lever is thus caused to contact the top projection 62 formed on the arms of the actuating lever 58, as will be understood by reference to FIGURES 7 and 8. The projections 62 are located on the left side of the pivot axis as shown in said figures, and the pressure of the lever 22 will cause the actuating lever 58 to move down until it rests on the bottom wall of the supporting structure. The down movement of the actuating lever 58 will positively open the contacts of the switch and thus the electric motor and pump, such as may be controlled thereby, is de-energized.

When the operator desires to again energize the motor and pump it is required that he cause the contacts of the switch to close. This is done by actuating the lever 64 shown in FIGURES 1, 4 and 6. The lever 64 is pivotally secured to the housing 65 of the switch and the end 66 of the lever is located under the pressure lever 22. The operator can rotate the lever 64 to elevate the pressure lever 22, and this action will free the actuating lever 58 and allow the coil springs 53 to close the contacts of the switch.

During the normal operation of the pressure switch the toggle member 38 will oscillate as the pressure varies from a pre-set minimum to a pre-set maximum. When the toggle member moves down it contacts the actuating lever 58 and, accordingly, moves the lever down to in turn open the switch contacts. When the toggle member moves up the pull rods 52 and the actuating lever also move up due to the action of the coil springs 53. The pressure lever 22 comes into action with the projections 62 only when a low pressure exists which is below the pre-set low pressure. Then the actuating lever is positively depressed into its low position and the switch contacts are opened although the toggle member is in an up position.

What is claimed is:

1. In a pressure switch, the combination with a supporting base structure, of a frame assembly secured to said base structure and providing a pair of spaced upstanding side frames, toggle mechanism pivotally supported by the side frames, said mechanism including a toggle member having pivotal movement in a direction parallel to the side frames, a contact block of insulating material fixedly supported by the side frames and located above the toggle member, a plurality of fixed contacts located within the contact block, at least one movable contact within the said block for coacting with the fixed contacts, a rod operatively connected at one end with the movable contact, the other end of the rod extending through the toggle member, an actuating lever pivotally supported by the frame assembly and located below the toggle member, the end of the rod extending through the toggle member having operative association with the actuating lever, and spring means in associated relation with the rod for yieldingly forcing the movable contact into closed relation with the fixed contacts.

2. In a pressure switch, the combination with a supporting base structure, of a frame assembly secured to said base structure and providing a pair of spaced upstanding side frames, a pressure lever pivotally engaging the side frames at one edge thereof and being adapted to oscillate in a direction parallel to the side frames, a toggle member pivotally engaging the side frames at the opposite edge thereof and also being adapted to oscillate in a direction

parallel to the side frames, resilient means disposed between the pressure lever and the toggle member and connecting therewith whereby the toggle member has movement in opposite directions between given extreme positions when the pressure lever is oscillated to a predetermined degree, a contact block of insulating material fixedly supported by the side frames, a plurality of fixed contacts located within the block and disposed in pairs, a movable contact mounted within the block for coaction with the pairs of fixed contacts, respectively, a rod operatively connected at one end thereof with each of the movable contacts, the other end of each rod extending through the toggle member, an actuating lever pivotally supported by the frame assembly and located below the toggle member, the end of each rod extending through the toggle member having operative association with the actuating lever, and a coil spring in encircling relation with each rod for yieldingly forcing its movable contact into closed relation with its pair of fixed contacts.

3. In a pressure switch as defined by claim 2, wherein each rod is a pull rod and wherein that end of each rod extending through the toggle member has operative association with the actuating lever by means of a hook end which is positioned under a side extension provided by the actuating lever, and additionally including a coil spring in compression relation with the oscillating end of the pressure lever.

4. In a pressure switch as defined by claim 2, wherein each rod is a pull rod and wherein that end of each rod extending through the toggle member has operative association with the actuating lever by means of a hook end which is positioned under a side extension provided by the actuating lever, a coil spring in compression relation with the oscillating end of the pressure lever, and said actuating lever having a top projection located below the oscillating end of the pressure lever, said pressure lever being adapted to contact the projection when oscillated in a down direction to a predetermined degree, whereby the actuating lever is also forced into an extreme down position and the pull rods are actuated to open the contacts.

5. In a pressure switch, in combination, a frame assembly providing spaced side walls, a pressure lever having side arms fulcrumed on the front edges of said side walls and located exteriorly of the walls, relatively movable contacts carried by the side walls above the lever, a toggle member fulcrumed on the rear edges of the spaced side walls and located between the walls, a spring connecting said pressure lever and the toggle member to pro-

vide a snap action toggle for said contacts, said toggle member having snap action in a direction parallel to the side walls when the pressure lever is oscillated in a direction also parallel to the side walls, an actuating lever also fulcrumed on the front edges of the side walls below the pressure lever and extending between the side walls below the toggle member for pivotal movement, at least one pull rod operatively connected at one end to the movable contacts and at its other end to the actuating lever, said pull rod extending through the toggle member so as not to interfere with the snap action of the toggle member, and said actuating lever having a projection on its top surface adjacent its pivotal axis for coaction with the pressure lever.

6. In a pressure switch, in combination, a frame assembly providing spaced side walls, a pressure lever having side arms fulcrumed on the front edges of said side walls and located exteriorly of the walls, a pair of fixed contacts carried by an insulating block secured to the side walls above the pressure lever, a movable contact strip mounted within the insulating block for coaction with the fixed contacts, a toggle member fulcrumed on the rear edges of the spaced side walls and located between the walls, a spring connecting the toggle member and the pressure lever to provide a snap action toggle for said movable contact strip, the said toggle member having snap action in a direction parallel to the side walls when the pressure lever is oscillated in a direction also parallel to the side walls, an actuating lever also fulcrumed on the front edges of the side walls below the pressure lever and extending between the side walls below the toggle member for pivotal movement, a pull rod operatively connected at one end to the movable contact strip and at its other end to the actuating lever, whereby down movement of the toggle member will effect similar movement of the actuating lever to cause the pull rod to open the contacts, and spring means associated with the pull rod and with the movable contact strip to yieldingly force the contact strip into contact closing relation with the fixed contacts.

7. In a pressure switch as defined by claim 6, wherein the actuating lever has a top projection relatively adjacent its pivotal axis for coaction with the oscillating end of the pressure lever.
